PRESS SYSTEM

Thomas F. Stacy, Piqua, Ohio, assignor to The French Oil Mill Machinery Co., Piqua, Ohio

Application May 15, 1933, Serial No. 671,197

27 Claims. (Cl. 60—52)

This invention relates to press systems and particularly to an improved manner of controlling the operations of a press. An object of the invention is to provide an improved system for hydraulic presses and the like, by which the operations of the press may be carried out more or less automatically, and which will be extremely simple, dependable, and inexpensive.

Another object of the invention is to provide an improved system for hydraulic presses and the like, in which changes in the operation of the press may be established quickly; with which the operation of the press will be rapid; with which there will be a maximum number of safeguards against injury to the operators, and with which the power stroke of the press may be continued for any selected and predetermined interval of time after the platen passes a selected point in its travel and then automatically stopped.

Another object of the invention is to provide an improved controlling system for hydraulic presses and the like with which the operator must have both hands out of dangerous positions with respect to the press before the press can be started; with which the operation of the platen may be stopped and held in stopped position, or reversed quickly at any point in its forward or pressing movement, and with which the platen may be held in any position under a selected pressure.

Various other objects and advantages will be apparent from the following description of an embodiment of the invention, and the novel features will be particularly pointed out herein-after in connection with the appended claims.

In the accompanying drawings, Fig. 1 is an elevation, partly in section, of a hydraulic press constructed in accordance with this invention, and having associated therewith a controlling system which is illustrated diagrammatically;

Fig. 2 is a sectional elevation, partially diagrammatic, of a simple form of a time limit relay;

Fig. 3 is an elevation of a portion of the press of Fig. 1, and a diagram of the control apparatus which is associated therewith and illustrating another embodiment of the invention by which a full automatic operation of the press may be obtained with a time dwell at the open position; and

Fig. 4 is a view similar to Fig. 3 except that the control device does not start an opening movement of the platen until the pressure in the main ram has reached a predetermined pressure.

In the embodiment of the invention illustrated in Figs. 1 and 2, the press is hydraulic and includes a base 1, and a platen 2 which is mounted for reciprocation on upright posts 3. The platen 2 is moved downwardly toward the base 1 by a

main ram formed of a plunger or piston 4 which reciprocates in a cylinder 5, the piston 4 being connected at its lower end to the platen 2. Rods 6 carried by the platen 2 extend upwardly therefrom and at their upper ends are connected by a yoke 7 which, in turn, is connected to a rod or piston 8 which reciprocates through one end of a cylinder 9. The piston 8 and cylinder 9, together, form a pull back ram which, operating through the yoke 7 and rods 6, serves to lift the platen 2 when fluid under pressure is admitted to the cylinder 9.

A reversible pump 10, which preferably is of variable delivery, is connected at one side by a pipe 11 to the cylinder 5 of the main ram, 15 and at its other side by a pipe 12 to the cylinder 9. The pipe 12 between the pump and the cylinder 9 includes a free check valve 13 which automatically opens to permit flow of fluid from the pump through the pipe 12 to the cylinder 20 9 and automatically closes to prevent reverse flow. The pipe 12, between the pump 10 and the valve 13, is connected by a pipe 14 to another check valve 15 which, in turn, is connected by a pipe 16 to a source 17 of a fluid under pressure. Since the fluids in such presses are usually liquid, the source of fluid may be a closed tank having an air chamber at the upper part thereof and otherwise filled with the operating liquid.

A pipe 18 opens into the lower part of the tank 17 and carries a valve 19 which, in the normal operation of the press, is always open, but constitutes a tank shut off valve which may be operated during repairs to the press. The pipe 18, after passing the valve 19, opens into 30 a differential check valve 20. This differential check valve 20 has a central or intermediate chamber 21 which opens into an end chamber 22 through an apertured seat 23, and also opens into an opposite end chamber 24 through an 35 apertured seat 25. A valve stem 26 extends through both the end chambers and the central chamber, and within the end chamber 22 carries the valve element 27 which moves within that end chamber into and out of closing or seating 40 position on the seat 23 upon reciprocation of the stem 26.

A valve element 28 abuts, but is separate from, the lower end of the stem 26 and moves back and forth in the other end chamber 24 into and out of engagement with the seat 25 whereby communication between the central chamber 21 and the end chamber 24 is broken or established by the position of valve element 28. A spring 28a 55 urges the valve element 28 into closed position on seat 25. Since the valve elements 27 and 28 are on opposite sides of the two valve seats 23 and 25, it follows that when the valve element 27 opens, the element 28 may or may not close, 60

and when valve element 28 closes, the valve element 27 must open.

It will thus be seen that the pipe 18 will conduct the operating liquid from the tank 17 to the central chamber 21 of the differential check valve 20, and from the chamber 21 the liquid will pass into one end chamber or the other, depending upon the relative positions of the valve elements 27 and 28. The valve stem 26 extends upwardly through the end chamber 22 and into a piston chamber 29, the passage from the end chamber 22 into the piston chamber 29 being provided with a suitable packing gland 30. The stem 26 at its end within the piston chamber 29 carries a piston or head 31 which reciprocates back and forth in the chamber 29 with the stem 26.

The piston 31 is forcibly reciprocated in the chamber 29 by an operating fluid, such as compressed air, the source of which is indicated by a compressed air tank 32. A pipe 33 connects the air tank 32 to the chamber of a valve box 34, and from this valve box pipes 35 and 36 lead to opposite ends of the chamber 29 and at opposite faces of the piston 31. A reciprocating valve element is provided in the box 34 to control the admission of fluid from the valve box alternately through the pipes 35 and 36 to opposite ends of the cylinder 29. For this purpose, the pipes 35 and 36 open into the chamber of the valve box 34 through suitable ports arranged along the path of travel of a reciprocating valve element 37 and, in addition, an exhaust port 38 also opens into the valve box through a suitable port between the ports of the pipes 35 and 36.

When the valve element 37 is in the position shown by full lines in Fig. 1, the chamber 39 in the face thereof which moves across the ports of the valve pipes will be in a position to establish communication between the exhaust pipe 38 and the pipe 36 which leads to the lower end of the chamber 29. At this time the port of the pipe 35 will be uncovered by the valve element 37 and, consequently, compressed air from the pipe 33 will pass through the valve box and pipe 35 into the upper end of the chamber 29 and force the piston 31 downwardly into the position shown in Fig. 1 and will hold it in that position.

If the valve element 37 is moved upwardly, it will uncover the port of the pipe 36 and will connect the port of the pipe 35 with the port of the exhaust pipe 38. This position is shown by dash lines in the drawings and when the valve is in this position, the upper end of the chamber 29 will be connected to atmosphere through the exhaust pipe 38 and the compressed air from the pipe 33 will pass through the pipe 36 to the lower end of the chamber 29 so as to force the piston 31 upwardly and thus move the valve element 27 away from its seat, and concomitantly release the valve element 28 for possible movement into closed position on its seat. Thus, by operating the valve element 37 one may cause an operation of the differential check valve to establish communication between the tank 17 and the two rams alternately or concomitantly. The delivery of the pump 10 may be reversed by reciprocation of a control rod 40 which extends into the chamber of a cylinder 41 and, within the cylinder 41, carries a piston or head 42. Another valve box 43, similar to the box 34, is provided to control the operation of the piston or head 42, and for this purpose pipes 44 and 45 extend from the opposite ends of the cylinder 41 to the valve box 43 and open into the chamber of the valve box through

suitable ports, the same as in the box 34. This box also has an exhaust pipe 46, and a pipe 47 connects the pipe 33, leading from the compressed air tank 32, to the chamber of the valve box 43.

A valve element 48 reciprocates in the box 43 between the full and dash line positions therein and the valve element 48 has a recess or chamber 49 in a face thereof which connects the exhaust pipe 46 alternately with the ports leading to the pipes 44 and 45. By shifting the valve element 48 in the box 43, the compressed air may be admitted alternately to the opposite ends of the cylinder 41 which causes reciprocation of the piston or head 42 in alternate directions to reverse the delivery of the pump 10. By reversing the delivery of the pump, the operating fluid or liquid may be transferred alternately between said rams and, thereby, the platen 2 may be moved in either direction.

The check valve 15 also serves as a by-pass valve, and for this purpose its valve element 50 is mounted for free movement toward and from its seat 51, so as to close automatically and prevent flow of an operating fluid from the pipe 14 into the pipe 16, yet open automatically and permit a reverse flow from the pipe 16 to the pipe 14. The valve element 50 abuts endwise against an operating stem 52 which depends through a packing gland 53 and terminates in a head 54. A spring 55 acting between the head 54 and the packing gland 53 yieldingly urges the stem 52 away from valve element 50 to allow element 50 to engage its seat 51.

An operating rod 56 is guided in a suitable bearing 57 on the base 1 and in a depending bracket 56A of the casing of the valve 15, so as to reciprocate endwise against the head 54. The rod 56 is limited in its downward movement by the engagement of a head on its upper end with the bracket 56A. The platen 2 is provided with an arm 58 which is adapted, as the platen 2 approaches its desired upward limited travel, to engage with a collar 59 adjustably carried by the rod 56. Thus, as the platen 2 approaches a selected point in its upward travel, it engages the collar 59 and through it lifts the rod 56 and stem 52 and cams the valve element 50 into open position for a purpose which will appear as the description proceeds. When the platen 2 starts downwardly again, it will release the collar 59 and the spring 55 assisted by gravity will move the rod 56 and stem 52 downwardly and release the valve element 50 which is then free to move into closed position. Various means may be employed for operating the valve box elements 37 and 48 to control the operations of the press, but in the drawings I have illustrated an electrical system of control which I find to be satisfactory. With such a system the valve element 37 is operated by a stem 60 which extends outwardly of the box and is operated by a suitable solenoid 61. Similarly, a rod 62 is connected to the valve element 48 of the valve box 43 and extends outwardly of the box and is operated by a solenoid 63. For this purpose, the rods 60 and 62 carry magnetic cores 64 and 65 which are operated in one direction by magnetic attraction of the solenoids 61 and 63, a reverse operation of the rods 60 and 62 being caused by gravity or with the assistance of springs 66.

Power for the operation of the solenoids is obtained from line wires L1 and L2 which may represent any suitable source of current. A wire 67 connects the power line L1 to one side of the solenoid 63 which controls the reversal of the

pump, and the other side of that solenoid is connected by a wire 68 to a contact 69. The contact 69 is connected by a switch bridge 70 to a contact 71, which in turn is connected by a wire 72 to the other power line L2. The switch bridge 70 is carried by and insulated from a stem 73 which is connected to the core 74 of a solenoid 75 which functions as a main relay. One end or side of the relay or solenoid 75 is connected to the wire 67 and through it to the power line L1, and the other side of the relay or solenoid 75 is connected by a wire 76 to the other power line L2. A pair of switches 77 are included in series with one another and with the wire 76, so that the circuit through the main relay 75 can only be closed by the closing of both switches 77. The switches are of any suitable type which are resiliently urged into open position, and together the two switches jointly control the main relay.

A holding or stick circuit for the main relay is provided for keeping the relay energized after the main relay circuit is closed, and for this purpose a bridge 78 is also carried by the stem 73 so as to bridge contacts 79 and 80. The contact 80 is connected by a wire 81 to one of the power wires, such as L2, and the other contact 79 is connected by a wire 82 to one side of a switch 83 which is yieldingly urged into a closed position by a spring 84.

The other side of the switch 83 is connected by a wire 85 to one side of an emergency return switch 86 which is yieldingly urged into closed position by a spring 87. The other side of the switch 86 is connected by a wire 88 to the wire 76 at a point between the switches 77 and the relay 75. This stick circuit may, therefore, be traced as follows:—From the power line L1, through wire 67, relay solenoid 75, wires 76 and 88, switch 86, wire 85, switch 83, wire 82, contact 79, bridge 78, contact 80 and wire 81 back to the other power line L2. It will thus be seen that this stick circuit is closed and opened by a bridge 78 which is operated by the relay when the relay is energized, and this circuit is also controlled by the normally closed switches 83 and 86.

One side of the solenoid winding 61 which controls the operation of the differential valve is connected by wire 89 to one of the power lines, such as L1, and the other side of the winding is connected by wire 90 to a contact 91. The contact 91 is connected at intervals by a bridge 92 to a contact 93 which, in turn, is connected by a wire 94 to the other power line L2. From this it will be observed that the solenoid winding 61 is connected to the power lines by the bridge 92 and this bridge forms part of an auxiliary relay 95. The winding of the relay 95 is connected at one side to the wire 89 which leads to the power line L1, and at its other side is connected by a wire 96 to a switch 97.

The other side of the switch 97 is connected by a wire 98 to a contact 99 which is connected at intervals by a bridge 100 to the contact 101 that, in turn, is connected by a wire 102 to the other power line L2. Thus, when the main relay 75 is energized, the bridge 100, which is carried by the stem 73 of the relay 75, is shifted into bridging relation with the contacts 99 and 101, thereby closing the circuit through the switch 97 and the auxiliary relay 95, which closing of this circuit, in turn, through the operation of this relay 95, closes the circuit of the solenoid

61 which controls the operation of the differential check valve.

The switch 97 may be shifted into open position against a neutral post 103, and a spring 104 acting on the switch 97 holds the switch in either open or closed positions yieldingly, owing to the fact that the spring 104 passes a dead center position while moving in either direction between open and closed positions. The switch 97 may be designated as a maintaining contact switch, and its function will appear as the description proceeds.

A suitable timing device is associated with the switch 83 which controls the stick circuit of the main relay, and is intended to open this stick circuit a predetermined and selected or adjustable interval of time after the platen has been started on the pressing stroke by the main ram. Such a timing device may be of any suitable type of which there are many on the market, including electric motors operating suitable cams through gear trains, such as are commonly employed in traffic signals, for example, or suitable clock mechanisms or time limit relays may be employed. In this particular example, for simplicity, a time limit relay has been illustrated and is shown diagrammatically in Fig. 1 and designated by the reference character 105.

The winding of this relay 105 is connected across the lines 89 and 90 which lead to the solenoid 61 which controls the operation of the differential check valve and, therefore, whenever the auxiliary relay 95 is closed through operation of the main relay 75, current will be supplied to the time limit relay at the same time that it is supplied to the solenoid 61 to effect a change in the position of the differential check valve. This time limit relay is arranged to engage and open the switch 83 automatically a selected and adjustable, predetermined length of time after current is supplied to the relay, and upon the opening of the stick circuit, the main relay 75 is automatically deenergized. Since the time limit relay is energized only while the main relay 75 is energized, it follows that when the stick circuit is opened, the time limit relay also will be deenergized and will return to normal position.

Any suitable form of time limit relay may be employed but one is shown more or less diagrammatically on a larger scale in Fig. 2 and may include a winding 106, a magnetically attractable core 107 carrying a piston 108 which reciprocates in a cylinder 109 to form therewith a dash pot. When the winding 106 is energized, it lifts the core 107 with its piston 108 and the rate of this upward travel is controlled by the entrance of air through an adjustable valve 110 into the cylinder 109, in the bottom thereof, that is, below the piston 108. When the piston 108, however, has nearly reached the position where it operates the switch 83, it uncovers a port 111 in the side of the cylinder 109, which relieves the partial vacuum created in the bottom part of the cylinder 109 by the upward movement of the piston 108, and the core 107 may then pass upwardly quickly and through a stem 112 thereof will engage and open the switch 83, thereby preventing arcing of the contacts of the switch.

Following opening of the switch 83 of the stick circuit, the winding 106 will be deenergized, as explained herein above, and thereupon the core 107 with its piston 108 will descend through the action of gravity, or through the assistance of one or more springs 113, which act upon a cross arm 114 carried by the stem 112. A check valve

115 controls an air escape passage leading from the bottom part of the cylinder 109, so that the air displaced by the downward movement of the piston 108 may freely escape, yet when the 5 ton 108 moves upwardly, the ball valve 115 will automatically close and compel all the air to enter the cylinder 109 through the adjustable valve 110. By adjusting the valve 110, the rate of travel of the piston 108 may be regulated, and thus the time interval following energization of the main relay before the stick circuit is opened may be regulated. The upper end of the stem 112 may be guided by rods 116 which have sliding engagement with the cross head 114.

15 It frequently happens that full automatic operation of the press is desired and, accordingly, I have provided means for reversing the press automatically when it reaches open position. In the illustrated example for accomplishing this 20 result, and referring to Fig. 1 of the drawings, a normally open switch 117 is provided on the frame or base 3 of the press in a position to be opened automatically by the platen when it reaches open position. Since the platen does not 25 always occupy the same open position and since the open position is determined by the position of the collar 59 on the rod 56, I have provided another collar 118 on the rod 56, the collar 118 being secured in the proper position on the rod 30 56 by a set screw or other suitable means. The collar 118 is set to engage and close the switch 117 automatically when the rod 56 is elevated through engagement of the arm 58 of the platen 2 with the collar 59, because the open position of 35 the platen is determined by the raising of the rod 56.

A wire 119 is connected to the wire 16, which is connected to one side of the double starting switch 11, and is also connected to one terminal 40 or contact of the switch 117. A wire 120 is connected to the other terminal or contact of the switch 117 and to a switch 121 which is yieldingly held in either of two positions, one of which is a closed position and the other of which is an 45 open position. This switch is shown in closed position by full lines in Fig. 1 and in open position by dash lines in the same figure. The switch is similar to the switch 97, and the spring 122, which is connected thereto, in passing dead center 50 or the pivot of the switch 121, yieldingly urges the switch in either position. The switch 121 is infrequently operated and hence is preferably so located as to be less accessible than the dual control switches 11. It also may be so disposed that 55 this operator must remove his hands from the work in order to reach it. It also may be placed anywhere and locked in either position so that the control of the press operations is normally in the switches 11. A wire 123 connects the other 60 terminal of the switch 121 with the wire 81 which leads immediately to the power line L2 which is, in effect, connecting the wire 123 to the other side of the double switch 11.

From this arrangement it will be observed that 65 the switch 117 is connected in parallel to the double switch 11, and that the closing of the switch 117 will perform the same function as the double switch 11. Thus, as the platen 2 reaches its upper or open position, as determined by the 70 adjustable collar 59, it lifts the rod 56 and closes the switch 117 which closes a shunt circuit around the double switch 11 and initiates a reversal of the travel of the platen. When the platen starts downwardly again, the rod 56 will 75 immediately be released and will descend. thus

releasing the switch 117 which automatically moves into open position, due to the resiliency of the contacts thereof.

If one desires to eliminate the automatic reversal of the platen when it reaches open or upper position, then one moves the switch 121 to the open position shown by dash lines in Fig. 1 whereupon the shunt circuit around the double switch 11 will be broken, and the closing of the switch 117 by the platen will no longer cause a 5 reversal of the direction of travel of the platen. It will be necessary then to close both switches 11 in order to start a downward movement of the platen.

The operation of the system which has been 15 illustrated will now be described. With the parts in the position shown in Fig. 1, the press is idle with the platen 2 elevated. At this time the pump 10 is delivering operating liquid through the pipe 12 to the pull back ram, but since the 20 by-pass check valve, at this time, is in open position, the delivered liquid will pass through the pipes 14 and 16 back into the tank 17, and from the tank 17 it will flow through the pipe 18 and the differential valve into the main ram cylinder 25 5 and thence through the pipe 11 to the intake side of the pump. At this time, the check valve 13 is closed because the pressure in the pull back ram cylinder 9 will be greater than that delivered by the pump, and since the valve element 30 27 is in closed position, the pressure in the pull back cylinder 9 will hold the platen 2 in its upper position.

If now one desires to cause a descent of the 35 platen 2, such as in a pressing operation, the attendant or operator operates both of the starting switches 11 simultaneously, because both of these switches must be closed at the same time in order to establish a circuit through the main relay 75. By having two separate switches 11, 40 it will be necessary for the operator to use both hands to operate both switches at the same time before the press can be started, and this is an important safety feature in that the operator must positively have both hands free of the press 45 in order to start a downward or pressing movement of the platen.

A momentary closing of the switches 11 is all 50 that is required because immediately upon the closing of the circuit of the main relay 75, the upward movement of the stem 73 of that relay, which immediately follows, causes a closing of three circuits through movement of the bridges 78, 70 and 100. The closing of the bridge 78 55 immediately closes the stick circuit which thereupon holds the main relay 75 energized, regardless of the immediate opening of the switches 11, since the latter are immediately returned to open position by their springs. At the same time that the relay 75 is energized, the bridge 70, which is 60 operated, closes the circuit through the solenoid 63, and this solenoid, by attracting its core 65, shifts the valve element 48 of the valve box 43 upwardly into the dotted line position shown in Fig. 1.

This movement of the valve element 48 causes the admission of compressed air through the pipe 44 to one end of the cylinder 41, forces the piston or head 42 to the left, (Fig. 1) causes a reversal in the delivery of the pump 10, and holds 70 the pump control in that position. At the same time, the main relay 75, through the closing movement of the bridge 100, closes the circuit through the auxiliary relay 95, and this relay 95 75 in turn operates the bridge 92 to close the circuit 75

to the time limit relay and the solenoid 61. The solenoid 61, when energized in this manner, shifts the valve element 37 into the dotted line position shown in the drawings and, in doing so, it connects the compressed air from the tank 32 to the pipe 36 which conducts it to the underside of the piston 31 of the differential valve.

This compressed air acting on the under side of the piston 31 forces the differential valve stem 26 upwardly or outwardly and, in doing so, moves the valve element 27 away from its seat, at the same time releasing the valve element 28 which is elevated upwardly into closed position on its seat 25 by its spring 28a. Since the liquid in the tank 17 is under pressure, because the liquid from the main cylinder 5 has been displaced into the tank 17 during the upward movement of the platen, and the air in the chamber in the top of the tank 17 has been compressed, this liquid from the tank 17, which is under considerable pneumatic pressure, may now pass through the differential check valve into the pull back ram cylinder 9 and also is sufficient to overcome the spring 28a and open the valve element 28 and flow into the main ram cylinder. The pressure in this cylinder 5 forces the platen 2 downwardly at a rapid rate, and the liquid displaced by the pull back ram escapes through valve seat 23 into passage 21.

At the same time, the pump 10 is drawing liquid from the tank 17, through the pipe 16, the valve 15, and the pipes 14 and 12, and delivers it through the pipe 11 to the main ram cylinder 5. A rapid movement of the platen 2 results because of the pressure created through the liquid delivered by both the pump and also the tank 17. As soon as the platen 2 encounters resistance to such an extent that the pressure required to cause further movement of the platen approximately equals the pressure then existing in the tank 17, 40 the liquid will no longer flow from the tank 17 directly into the main cylinder 5, because the pressure is approximately equal in both tank and ram cylinder, and thereupon the valve 28 will be closed by its spring 28a.

45 The operating liquid will then move from the tank 17 through the pipe 16, the valve 15, the pipes 14 and 12, through the pump, and thence through the pipe 11 to the main cylinder 5. When the platen 2 started downwardly, it released the collar 59, and the rod 56 then dropped, but the valve element 50 remained open owing to the suction through the pipes 12 and 14 created by the pump, and the liquid passing through the pipe 16 holds the valve element 50 lifted. The 50 continued operation of the pump 10 will cause the gradual building up of pressure in the cylinder 5 and an increasing pressure on the platen 2.

The pump 10 is of a well known reversible and variable delivery type and automatically sets 60 itself to neutral, or only sufficient delivery to offset leakage, when the pressure in the delivery side to the main ram reaches a selected, but adjustable, maximum pressure. This may be accomplished, for example, by connecting a branch pipe 65 a to the pipe 11, and to a small cylinder b. A piston or ram c reciprocating in the cylinder b is connected to a pair of control levers d to operate them to neutral delivery position against the action of a spring e that reacts between an 70 adjustable abutment f upon the control rod 40 and a yoke g connecting the control levers d. The rod 40 passes freely through the yoke g and terminates in a head 40a so that the levers d may be positively moved to reverse the pump and cause an operation of the pull back ram and a

return of the platen. When the rod 40 is shifted to the left (Fig. 1) by operation of the piston 42, the spring e is compressed and forces the levers d yieldingly into positions in which the pump delivers to the main ram. By adjusting the abutment f to increase the pressure on the spring e, the greater will be the pressure required on the main ram, before the control levers d are shifted to approximately neutral delivery position.

5 At the same time that the downward movement of the platen 2 was initiated by the closing of the main relay 15, the time limit relay or other timing device was rendered effective and a predetermined and adjustable length of time thereafter it opened the switch 83 of the stick circuit 10 and caused a deenergization of the relay 15. Thereupon the bridges 78, 70 and 100 all moved into open position and broke the stick circuit at another point and opened the circuits controlling the solenoids 61 and 63. Thereupon the springs 66 and gravity operate the valve elements 37 and 48 of the valve boxes back to the full line positions and, in doing so, the compressed air is shut off from the pipes 36 and 44 and admitted to the pipes 35 and 45.

25 At the same time that the pipes 36 and 44 are connected to exhaust, so that there will be no back pressure on the pistons 31 and 42. Compressed air is admitted to the pipes 35 and 45 and causes movement of the piston 42 to the right and 30 reverses the delivery of pump 10. Thereupon the pump 10 draws liquid from the main cylinder 5, through the pipe 11, and delivers it through the pipe 12 and the valve 13 to the pullback cylinder 9, through the valve cavity 22, the valve cavity 35 21, and back into the tank 17. In this manner the pressure in the press cylinder is dropped to zero. At the same time that compressed air is admitted to move the piston 42 it is admitted 40 to operate piston 31 of the differential valve into the full line position shown in the drawings. As soon as the pump has dropped the pressure by pumping out of the main cylinder, the large valve 28 with the pressure removed from its face 45 is free to open. The piston 31 then forces the valve element 27 into closed position and the stem 26 forces the valve element 28 into open position.

50 At this time the valve element 50 of the bypass valve 15 closes automatically so as to prevent flow from the pipe 14 into the pipe 16. The check valve 13 opens freely at this time and the liquid delivered to the pull back cylinder 9 will force the pull back piston or ram 8 upwardly and lift the platen 2. Since the liquid displaced by the main ram or piston 4 is greater than that necessary to 55 supply the pump for delivery to the pull back cylinder, the excess liquid in the main cylinder 5 will pass directly through the valve seat 25 and the differential valve chamber 21, into the pipe 18, thence back into the tank 17, where the air 60 in the tank 17 is compressed and a new initial operating pressure built up.

65 The return movement of the platen 2 is, therefore, relatively rapid. When the platen approaches the desired upward limit of its travel, 65 the arm 58 of the platen engages the collar 59 which has been adjusted into a selected position, and as the platen 2 moves further, the rod 56 is lifted and the stem 52 elevated to force the check valve element 50 of the by-pass valve 15 into open 70 position. Thereupon, the delivery of the pump to the pipe 12, instead of passing into the pull back ram, will take the path of least resistance through the pipe 14, valve 15, and pipe 16, to the tank 17, and since the check valve 13 will then 75

automatically close, the liquid will be locked in the pull back cylinder 9 and will hold the platen 2 elevated in this position. The platen will remain in this position until a new operation of 5 the press is desired.

It will be noted that current is consumed for the electrical devices only when the platen is moving downwardly in a pressing direction, and none will be used while the press is in idle position, as shown in the drawings. If, for any reason, it is desired to stop the downward movement of the platen after a downward movement has been started and before it has been completed, this may be done by manually opening the emergency return switch 86 which breaks the stick circuit and causes an immediate return movement of the platen, the same as would be caused by the opening of the switch 83.

If one desires to stop the press at any point in 20 the downward movement of the platen and hold the platen in that position, the switch 97 is moved into open position, shown by the dash lines in Fig. 1, at the desired point in the downward movement of the platen 2. When this happens, the 25 auxiliary relay 95 will be deenergized, and this opens the circuits to the solenoid 61 and the time limit relay or timing device 105. The current will continue indefinitely to the solenoid 63 because there is now nothing to break the stick circuit until the manual switch 86 is opened, or the 30 switch 97 is returned to closed position. When the auxiliary relay 95 opens the circuit controlled thereby, the valve element 37 in the valve box will return to the full line position in the drawings and will reverse the differential valve. This 35 causes a closing of the valve element 27 on its seat and a forced opening of the valve element 28.

Since the delivery of the pump was not changed, it will continue to deliver the operating liquid to 40 the main cylinder 5 but since the differential valve element 28 was opened, the operating liquid will travel through the cylinder 5 and back to the tank in an idle circuit, so that no further downward movement of the platen will occur because oil in the pull back ram can not escape. 45 No upward or return movement can occur until the pump is reversed and, therefore, the platen 2 will remain in this position in which it is stopped until the switch 86 is opened or the switch 97 is closed. The switch 97 thus may properly be called a maintaining switch because, by opening it, the 50 press is maintained or held in any position it may be in during a pressing movement.

In the foregoing statement of the operation, it 55 has been assumed that the switch 121 is in open position, and that there has been no automatic reversal of the press as the platen reaches open position. If now one desires to have automatic operation of the press, the switch 121 is moved 60 into closed position, shown by full lines in Fig. 1, and thereupon whenever the platen reaches open position, and which open position may vary as determined by the adjustment of the collar 59 on the rod 56, the closing of the switch 117 upon the 65 elevation of rod 56 will automatically reverse the press and start a new downward movement in the same manner that the platen would be started downwardly by an operation of the double switch 71. This automatic reversal at open position 70 can be eliminated at any time merely by shifting switch 121 back into open position.

Referring next to Fig. 3, the press is of the same construction as shown in Fig. 1, but only a fragmentary portion of it is illustrated in order 75 to explain a modification in the details of the

control thereof. In Fig. 3 parts performing the same functions as in Fig. 1 have been given the same reference characters, and will not be further described in detail. The control system shown in this Fig. 3 is the same as in Fig. 1, except that a switch 124 is provided and is connected by wires 125 and 126 to opposite sides of the double switch 11. For example, wire 126 is connected to the wire 88 or the wire 76, and the wire 125 is connected to the power line L2 or to the wire which 10 connects the power line L2 to one side of the double switch 11. The switch 124 is normally held in open position by a spring 127.

A time limit relay 128 is disposed in a position to close the switch 124 when the relay is energized, and the coil or solenoid 129 of this time limit relay 128 is connected at one side by wire 130 to the power line L2, and at the other side is connected to the wire 123 instead of having the wire 123 connected to the power line L2. In 20 other words, this arrangement is exactly the same as in Fig. 1 except that the switch 124 has been added and the time limit relay 128 has been placed in series in the wire 123, so that when the reversing circuit, which is rendered operative 25 by the platen as it reaches open position, is energized, it will energize the time limit relay 128 and after the lapse of a selected and adjustable period of time, the switch 124 will be closed automatically and a downward movement of the platen 30 started a selected and predetermined interval of time after the platen has reached its open position. This provides for a brief period of rest for the platen in its open position, and this period of time may be varied by adjusting the time 35 limit relay to vary the period of time which will elapse after the relay is energized before the switch 124 is closed by it. This time limit relay 128 may be identical or similar in construction to the time limit relay 106 which controls the 40 stick circuit for relay 75. While the windings of the relays 75 and 129 are in series in a common circuit in one operating condition when switch 117 is closed by the platen while switch 121 is closed, the relay 75 will not be operated because 45 the voltage in that common circuit is divided between the windings of both relays 75 and 129, which means that relay 75 has only a portion of its lifting power. Since relay 75 must operate against a fixed or definite load, it is so designed 50 that when subjected to a current at such a reduced voltage it will not be operated, but when full voltage is applied, such as by closing switches 77, it will be operated. The relay 129 may, of course, be designed to operate at either the reduced or full voltage. The operation of the control system shown in Fig. 3 is otherwise the same as described for Fig. 1.

In the embodiment of the invention shown in Fig. 4, the arrangement of the control system is 60 identical with that shown in Fig. 3, except that the switch 83 of the stick circuit for the main relay 75, instead of being opened by the time limit relay 106, as in Figs. 1 and 3, a selected 65 interval of time after the platen starts its downward or forward stroke, will be opened automatically after the pressure on the main ram 4 reaches a selected and adjustable, predetermined pressure. To accomplish this, the time limit relay 106 of Fig. 3 is removed and in its place a pressure responsive mechanism is substituted. This mechanism includes a hydraulic cylinder 131 in which reciprocates a piston or plunger 132 in a direction to engage and open the stick circuit switch 83.

A pipe 133 connects the interior of the cylinder 131 to the interior of the cylinder 5, and therefore the pressure in the cylinder 131 will be directly responsive to the pressure in the main cylinder 5. As the pressure in the cylinder 131 increases, it will force the plunger 132 upwardly or outwardly and cause it to open the stick circuit switch 83. The plunger 132 carries a yoke 134 and this yoke forms one end of a frame 135 which extends across the closed end of the cylinder and carries an adjustable abutment 136, between which and the end of the cylinder is disposed a compression spring 137. The upward movement of the plunger 132 is, therefore, resisted by the spring 137 and, hence, the plunger 132 will not move upwardly and open the stick circuit switch 83 until the pressure in the main cylinder 5 has become great enough, when transmitted to the cylinder 131, to overcome the resistance of the spring 137. This resistance, which must be overcome, may be varied by adjusting the adjustable abutment 136, which may include a screw threaded through the frame 135.

Thus, when the pressure in the main cylinder 5 of the press reaches a predetermined and selected pressure, the plunger 132 will open the stick circuit switch 83, thereby deenergizing the main relay 15 and initiating an upward or return movement of the platen. From this it will be seen that the termination of the downward movement of the platen will be automatically made after the pressure on the platen has reached a selected pressure, instead of a predetermined length of time after the downward movement of the platen began, as in the device shown in Figs. 1 and 3. Otherwise, the operation is the same as in Figs. 1 and 3 and similar parts have corresponding characters.

In the system which has been hereinabove described, the timing relay or device 105, which automatically causes a reversal in the direction of travel of the platen and initiates an upward movement thereof, begins to operate at the beginning of the downward or pressing movement of the platen. The speed of closing of the press is not always constant, for example, varying with the temperature and consequent change in the viscosity of the oil and, therefore, it may at times be desirable to start the timing device in operation at approximately the end of the closing movement of the press and just before the real pressing operation begins.

To make this possible, I may provide on the platen 2 an arm or control finger 138, Fig. 1, which is mounted on the platen for limited vertical adjustment such as by making it slideable upon the vertical guide rod 139 and securing it in different adjustable positions thereon by a set screw 140. The finger 138 thus moves with the platen 2 in both directions. In the path of travel of the finger 138, I mount a switch device 141 which is closed by the finger 138 at various selected points in the downward travel of the platen, the switch remaining closed during the remainder of the downward travel of the platen. This switch is included in series in the circuit of the time limit relay winding 106.

Any suitable switch for this purpose may be employed but, by way of example, I have shown a lever or member pivotally mounted at 142 upon a suitable part of the press frame. The switch member has two arms 143 and 144. A spring 145 is connected to the switch member and to the frame of the press in a manner to pass dead center or the pivot 142 of the switch when the switch

member is oscillated. A stop pin 146 limits the clockwise movement of the switch member so as to place the arm 143 thereof in approximately a horizontal position in the path of travel of the finger 138. The spring 145 yieldingly holds the switch in this position.

When the finger 138 moves downwardly, it engages the arm 143 and rocks the switch member until the spring 145 passes dead center, whereupon the spring automatically snaps the switch further in the same direction until the arm 143 engages a contact or switch terminal 147 suitably mounted on the press frame. When the switch member is stopped in this position, the arm 144 of the switch member is then above or behind and in the path of travel of, the finger 138 and the arm 143 is out of the path of travel of the finger 138. The spring 145 holds the switch member in this position. A wire 148 connects the wire 99 to the switch member 141 and a wire 149 connects the contact or terminal 147 to one side of the time limit relay 106, the other side of the time limit relay 106 being connected to the wire 89.

With this arrangement, the winding 106 will not be energized when the solenoid winding 61 is energized, but when the platen 2 reaches a selected intermediate position in its movement in a pressing direction, it will rock the switch member 141 into closed position and leave it in that position during the remainder of the downward or pressing movement of the platen. The time limit relay then functions and opens the stick circuit a predetermined time after the platen passes the selected intermediate position. When the stick circuit is opened in this manner, the mechanism sets the press controls to retract the platen 2 and, as the platen 2 travels upwardly, the finger 138 will engage the arm 144 of the switch member 141 and will rock it until the spring 145 again passes dead center position, whereupon the spring will snap the switch member into the position shown in Fig. 1 in which the arm 143 is in the path of travel of the finger 138 and the arm 144 is out of the path of travel of the finger 138. The circuit of relay 106 at this time is open.

If one desires to incapacitate this delayed starting of the timing device, it is merely necessary to close a switch 150 which is connected across the wires 148 and 149 and thus shunts the switch so that the time limit relay 105 will begin to function immediately at the beginning of the downward movement of the platen. By adjusting the finger 138 vertically on the platen, the point in the travel of the platen at which the switch is operated to start the functioning of the time limit relay may be adjusted or varied. Similar means for accomplishing the delay in the starting of the timing device may also be applied to the construction shown in Fig. 3.

It will be obvious that various changes in the details, which have been herein described and illustrated in order to explain the nature of the invention, may be made by those skilled in the art within the principle and scope of the invention, as expressed in the appended claims.

I claim:

1. In a hydraulic press system, a main ram, a pull back ram, a platen operated by said rams, a source of fluid, a reversible pump, connections between said rams, said source and said pump, by which fluid may be delivered under pressure in either direction between said rams selectively to

cause operation of said platen in either direction, and automatic means free of control by the pressure of fluid in either ram and rendered effective by the platen as the platen leaves a predetermined adjustable position during a pressing operation, for reversing said pump and causing operation of said rams a selected interval of time thereafter.

2. In a hydraulic press system, a main ram, a pull back ram, a platen operated by said rams in alternate directions, a source of fluid, a reversible pump, connections between said rams, said source and said pump and forming a hydraulic circuit by which fluid under pressure may be delivered under pressure in either direction between said rams selectively to cause operation of the platen in either direction, a reservoir connected to said rams, a differential valve having two check valve elements opening to pass fluid from said reservoir to each ram and automatically closing to prevent return flow, means for operating said valve and reversing said pump to cause a reversal in the direction of travel of said platen, and means free of the pressure upon said main ram and also free of the speed of the operation of said main ram, for automatically operating said reversing means and causing a return operation of said platen a selected interval of time after said platen passes a selected and adjustable position in a pressing direction.

3. In a hydraulic press system, a main ram, a pull back ram, a platen operated by said rams in alternate directions, a source of operating fluid, pumping means, connections between said rams, said source and said means by which fluid may be delivered under pressure to said rams selectively, electrical means for controlling the delivery of operating fluid to one ram or the other and including a controlling circuit, and timing means exclusive of the hydraulic circuit but set in operation automatically when said electrical means is operated to initiate a pressing movement of said platen, and operable to cause a return movement of said platen a predetermined length of time after the pressing movement of said platen is initiated.

4. In a hydraulic press system, a platen, hydraulic rams connected to said platen to operate it in both directions, means including a continuously operating pump connected to said rams for operating said platen in alternate directions depending upon which ram receives fluid from said pump, means for controlling the delivery of fluid to said rams selectively so as to control the direction of operation of said platen, and a timing device exclusive of the pump but set in operation automatically when said controlling means is operated to change the delivery of fluid from said pump from one of said rams to the other and cause movement of the platen in a pressing direction, for causing a reversal of the platen a predetermined time after the desired movement of the platen in said pressing direction is initiated.

5. In a hydraulic press system, a platen, hydraulic rams connected to said platen to operate it in both directions, means including a continuously operating pump connected to said rams for operating said platen in alternate directions depending upon which ram receives fluid from said pump, means for controlling the delivery of fluid to said rams selectively so as to control the direction of operation of said platen, and a timing device connected to said controlling means

set into operation automatically by said platen while said platen is traveling in a pressing direction for changing the delivery of fluid by said pump from one ram to the other and causing a reversal of the direction of travel of the platen a predetermined interval of time thereafter, regardless of the operating pressure upon, or rate of travel of, said platen.

6. In a hydraulic press system, a platen, means for operating said platen in alternate directions, means for controlling the direction of operation of said platen, a timing device exclusive of said operating means, set in operation automatically when said controlling means is operated to cause movement of the platen in one direction, for causing a reversal of the platen a predetermined time after the desired movement of the platen in said one direction is initiated, and means for interrupting the action of said timing device and causing a return of said platen selectively at any time, whereby in an emergency the return of the platen may be accomplished before the expiration of said predetermined time.

7. In a hydraulic press system, a platen, hydraulic means for operating said platen in alternate directions, a pump, means connecting said pump and hydraulic means for causing operation of said platen in alternate directions, a control device for controlling the delivery of said pump to said hydraulic means for determining the direction of the operation of said platen, electrical means for controlling the activity of said control device, and means including said electrical means, a circuit and a relay for controlling the activity of said electrical means so as to thereby control the operation of said platen, a stick circuit for said relay, a time limit relay operable on said stick circuit to open it a predetermined length of time after the closing of the first relay, and a circuit for said time limit relay controlled by the first mentioned relay.

8. In a hydraulic press system, a platen, means for operating said platen in alternate directions, means including a relay and its circuit for controlling said operating means and having said circuit closed when operation of said platen in one direction is desired, switch means for said relay circuit for closing it, a stick circuit for said relay, means including a timing device operable upon said stick circuit for opening it a predetermined interval of time after the energization of said relay and thereby causing a reversal in the direction of operation of said platen.

9. In a hydraulic press system, a platen, means for operating said platen in alternate directions, means including a relay and its circuit for controlling said operating means and having said circuit closed when operation of said platen in one direction is desired, switch means for said relay circuit for closing it, a stick circuit for said relay, means including a timing device operable upon said stick circuit for opening it a predetermined interval of time after the energization of said relay thereby causing a reversal in the direction of operation of said platen, and means operable separately from said stick circuit for stopping travel of said platen in a pressing direction, at any point in said travel and holding it at that point at any time for emergency purposes.

10. In a hydraulic press system, a platen, rams operating said platen in opposite directions, means including continuously operating pumping means connected to said rams for delivering operating fluid to said rams alternately, and thus operating said platen in alternate directions, a

source of operating fluid, connections from said source to both rams, valve means in said connections, a relay and its circuit, means controlled by said relay for changing the delivery of said pumping means from one ram to the other, means also controlled by said relay for changing said valve means concurrently with the change in said pumping means, switch means for closing said relay circuit to initiate an operation of said platen in one direction, a stick circuit for said relay, and means including a timing device operable upon said stick circuit for opening it a predetermined interval of time after the energization of said relay and thereby causing a reversal in the direction of operation of said platen.

11. In a hydraulic press system, a platen, rams operating said platen in opposite directions, means including continuously operating pumping means connected to said rams for delivering operating fluid to said rams alternately, and thus operating said platen in alternate directions, a source of operating fluid, connections from said source to both rams, valve means in said connections, a relay and its circuit, means controlled by said relay for changing the delivery of said pumping means from one ram to the other, means also controlled by said relay for changing said valve means concurrently with the change in said pumping means, switch means for closing said relay circuit to initiate an operation of said platen in one direction, a stick circuit for said relay, and means including a timing device operable upon said stick circuit for opening it a predetermined interval of time after the energization of said relay and thereby causing a reversal in the direction of operation of said platen, and means to operate said valve means while said relay remains unchanged and separately from said means for changing the direction of delivery of said pumping means.

12. In a hydraulic press system, a platen, means for operating said platen in alternate directions, means controlling the direction of operation of said platen and including a relay and its circuit, switch means for closing the circuit of said relay to initiate an operation of said platen, a stick circuit for said relay, and means including a timing device controlled by said relay and having a switch in series in said stick circuit which it opens for opening said stick circuit a predetermined length of time after said stick circuit is closed, whereby the relay will be deenergized and travel of the platen in one direction stopped.

13. In a hydraulic press system a platen, means for operating said platen in alternate directions, means controlling the direction of operation of said platen and including a relay and its circuit, switch means for closing the circuit of said relay to initiate an operation of said platen, a stick circuit for said relay, a time limit relay operable to open said stick circuit a predetermined length of time after being set in operation, a circuit for said time limit relay in turn controlled by the first relay, so that the time limit relay will be automatically set in operation upon the energization of the first relay and closing of said stick circuit.

14. In a hydraulic press system, a platen, a main ram and a pull back ram connected to said platen to operate it in alternate directions, a source of fluid under pressure connected to both of said rams, means including a valve device operable to connect said source alternately to said rams, pumping means connected to said rams for transferring fluid between said rams

in either direction under pressure so as to cause operation of said platen in either direction; motor means for changing the delivery of said pump from one ram to the other, motor means for forcibly operating said valve from one position to another, means including a common control element for causing operation of both of said motor means at substantially the same time, the control of both of said motor means causing the positioning of said valve to connect said source to said main ram when said pump is delivering fluid to said pull back ram, and means for additionally causing an operation of the second of said motor means during a pressing movement of said platen to position said valve to connect said source to said main ram while the first motor means is in a position to cause delivery of fluid by said pumping means to said main ram, whereby said platen may be held in any position.

15. In a hydraulic press system, a platen, hydraulic means for moving said platen in alternate directions to and from pressing position, means including a relay operable on said means for controlling the direction of travel of said platen, a regular circuit for said relay which when closed will energize said relay and initiate a forward movement of said platen, a stick circuit for holding said relay energized, means for opening said stick circuit to terminate said forward movement of the platen and cause a reverse movement of the platen, and means including an electric circuit and a switch therein but operated by said platen during a return movement of said platen for closing said relay regular circuit and causing a reversal of travel of said platen and initiate another forward movement of the platen a predetermined and substantial length of time after operation of said switch by said platen.

16. In a hydraulic press system, a main ram, a pull back ram, a platen operated by said rams in alternate directions, a source of operating fluid, pumping means, connections between said rams, said source and said means by which fluid may be delivered under pressure to said rams selectively, electrical means for controlling the delivery of operating fluid to one ram or the other and including a controlling circuit, timing means free of control by the pressure on said platen and set in operation automatically by said electrical means when said electrical means is operated to initiate a pressing movement of said platen, and operable to cause a return movement of said platen a predetermined length of time after the pressing movement of said platen is initiated, and switch means for said circuit, operable by said platen at the end of its return movement for causing automatically a reversal of the platen and its start on a forward movement.

17. In a hydraulic press system, a platen, hydraulic means for operating said platen in alternate directions, means for controlling the direction of operation of said platen, and means exclusive of said hydraulic means and operable by said platen during a return movement for changing said controlling means to initiate a forward movement of said platen automatically after the lapse of an appreciable length of time following completion of the return movement of said platen, said last named means including a control element adjustable into different selected positions along the path of travel of said platen.

18. In a hydraulic press system, a platen, hydraulic means for operating said platen in alternate directions, means for controlling the direction of operation of said platen selectively,

- means operating said controlling means to reverse the direction of operation of said platen and cause a return movement thereof, means operable by said platen at the end of a return movement for setting said controlling means to stop said platen, and a timing device, exclusive of said hydraulic means, set in operation by the platen at approximately the completion of a return movement for operating said controlling means 5 to cause a forward movement thereof of a predetermined and substantial interval of time after said platen substantially completed its return movement.
19. In a hydraulic press system, a platen, hydraulic means including a continuously operating reversible pump, for operating said platen in alternate directions by hydraulic pressure from said pump, means for reversing said pump to control the direction of operation of said platen selectively, and timing means set into operation automatically by said platen at an intermediate point in its movement in one direction for operating said controlling means to reverse the delivery of said pump and thereby the direction of operation 10 of said platen, a predetermined interval of time thereafter.
20. In a hydraulic press system, a platen, a main ram and a pull back ram connected to said platen for operating it in alternate directions, a reversible, variable delivery pump, pipes connecting said pump to said rams for transferring fluid between the rams alternately upon reversal of the direction of delivery of the pump to control the direction of travel of said platen, a 15 check valve in the pipe connecting said pump to the pull back ram, opening to pass fluid from the pump to that ram and closing automatically to prevent reverse flow, a source of fluid, pipes connecting said source to each of said rams and to that side of the pump which is connected through said check valve to the pull back ram, and valves in the last mentioned pipes operable to prevent escape of fluid from the pull back ram and by-pass fluid delivered by the pump towards 20 the main ram, back to said source and pump, for stopping and holding said platen in any intermediate position during its pressing movement with the pump delivering at approximately the same rate and in the same direction.
21. In a hydraulic press system, a platen, rams connected to said platen for operating it in alternate directions, a continuously operating pump, connections from said pump to said rams, a source of fluid, a conduit from said source to each ram, a differential valve having two valve 25 elements connected in parallel in said conduits and effective when open to pass fluid from said source to said rams, fluid actuated means operating outside of said valve elements for forcibly operating said differential valve elements and for changing the delivery of fluid from said pump to one ram or the other depending upon which ram is to be operated, electrical means for controlling said fluid actuated means to cause forcible operation of said differential valve and to alter the direction of transfer of fluid from one ram to the other in a predetermined relation to one another that will cause operation of said platen in alternate directions, and means also controlling said fluid actuated means for effecting forcible operation of said differential valve out of said predetermined relation while continuing the delivery of fluid to one of said rams, whereby said platen may be selectively stopped and held 30 in any intermediate position while travelling in

one direction, and travel in the same direction resumed when desired.

22. In a hydraulic press system, a platen, a main ram connected to said platen for operating it in a pressing direction, a pull-back ram for retracting the platen, a continuously operating pump connected to said rams for transferring fluid in either direction between them to determine the direction of operation of said platen, a reservoir, a differential valve having two valve elements connected between said reservoir and said rams, a motor for forcibly operating said differential valve elements and connecting said reservoir alternately to said rams, means including another motor for changing the delivery of fluid from said pump from one ram to the other, means including an electrical circuit for operating said motors in a desired relation to one another and for causing travel of said platen in alternate directions, and means for additionally controlling the motor of the differential valve and operating said valve elements to close communication between said pull-back ram and reservoir and to open communication between said main ram and reservoir while said pump is delivering fluid to said main ram, whereby said platen may be stopped and held in any selected point in its travel in a pressing direction while said pump is delivering fluid to said main ram.

23. In a hydraulic press system, a platen, a main ram for operating said platen in a pressing direction, a pull-back ram for retracting said platen, a reversible delivery pump connected to said rams for transferring fluid between them in either direction, a check valve in the connection from said pump to the pull-back ram for restricting flow therethrough toward said pull-back ram, a reservoir, branch connections therefrom to said rams, a differential valve having two valve elements, one in each of said branch connections for connecting said reservoir alternately to said rams, a pipe connecting said reservoir to said pump at the side connected to said pull-back ram and between the pump and the check valve, a free check valve in the pipe between said reservoir and pump and restricting flow therethrough to a direction toward said pump, means for reversing the pump to cause operation of said platen in alternate directions, and means for forcibly operating said differential valve elements to close communication between said pull-back ram and reservoir while said pump continues to deliver fluid to said main ram whereby said platen may be stopped and held in any intermediate position in a pressing movement, and resumption of a pressing movement selectively obtained by a return of the differential valve elements to the positions in which the valve elements connect the reservoir to said pull-back ram and close communication between said main ram and reservoir.

24. In a hydraulic press system, a platen, a main ram for operating said platen in a pressing direction, a pull-back ram for retracting said platen, a reversible delivery pump connected to said rams for transferring fluid between them in either direction, a check valve in the connection from said pump to the pull-back ram for restricting flow therethrough toward said pull-back ram, a reservoir, branch connections therefrom to said rams, a differential valve having two valve elements, one in each of said branch connections for connecting said reservoir alternately to said rams, a pipe connecting said reservoir to said pump at the side connected to said pull-back ram

and between the pump and the check valve, a free check valve in the pipe between said reservoir and pump and restricting flow therethrough to a direction toward said pump, means for reversing the pump to cause operation of said platen in alternate directions, means for forcibly operating said differential valve elements to close communication between said pull-back ram and reservoir while said pump continues to deliver fluid to said main ram whereby said platen may be stopped and held in any intermediate position in a pressing movement, and resumption of a pressing movement selectively obtained by a return of the differential valve elements to the positions in which the differential valve connects the reservoir to said pull-back ram and closes communication between said main ram and reservoir, and means operated by said platen during a retraction movement for forcibly opening the free check valve and stopping the retraction of said platen while said pump is delivering said fluid toward said pull-back ram.

25. In a hydraulic press system, a platen, a main ram for operating said platen in a pressing direction, a pull-back ram for retracting said platen, a reversible delivery pump connected to said rams for transferring fluid between them in either direction, a check valve in the connection from said pump to the pull-back ram for restricting flow therethrough toward said pull-back ram, a reservoir, branch connections therefrom to said rams, a differential valve having two valve elements, one in each of said branch connections for connecting said reservoir alternately to said rams, a pipe connecting said reservoir to said pump at the side connected to said pull-back ram and between the pump and the check valve, a free check valve in the pipe between said reservoir and pump and restricting flow therethrough to a direction toward said pump, means for reversing the pump to cause operation of said platen in alternate directions, means for forcibly operating said differential valve elements to close communication between said pull-back ram and reservoir while said pump continues to deliver fluid to said main ram whereby said platen may be stopped and held in any intermediate position in a pressing movement, and resumption of a pressing movement selectively obtained by a return of the differential valve elements to the position in which they connect the reservoir to said pull-back ram and close communication between said main ram and reservoir, means operated by said platen during a retraction movement for forcibly opening the check valve in said pipe connecting said reservoir to said pump and stopping the retraction of said platen while said pump is delivering said fluid toward said pull-back ram, electrical means for controlling the direction of delivery of said pump and of the forcible operation of said differential valve elements to control the direction of travel of said platen, said electrical means being operable by said platen during a retraction movement thereof for automatically reversing the delivery of said pump and forcibly operating said differential valve to automatically initiate a pressing operation of said platen after a desired return movement of the platen.

26. In a hydraulic press system, a platen, a main ram for operating said platen in a pressing direction, a pull-back ram for retracting said platen, a reversible delivery pump connected to

said rams for transferring fluid between them in either direction, a check valve in the connection from said pump to the pull-back ram for restricting flow therethrough toward said pull-back ram, a reservoir, branch connections therefrom to said rams, a differential valve having two valve elements, one in each of said branch connections for connecting said reservoir alternately to said rams, a pipe connecting said reservoir to said pump at the side connected to said pull-back ram and between the pump and the check valve, a free check valve in the pipe between said reservoir and pump and restricting flow therethrough to a direction toward said pump, means for reversing the pump to cause operation of said platen in alternate directions, means for forcibly operating said differential valve elements to close communication between said pull-back ram and reservoir while said pump continues to deliver fluid to said main ram whereby said platen may be stopped and held in any intermediate position in a pressing movement, and resumption of a pressing movement selectively obtained by a return of the differential valve elements to the position in which they connect the reservoir to said pull-back ram and close communication between said main ram and reservoir, means operated by said platen during a retraction movement for forcibly opening the check valve in said pipe connecting said reservoir to said pump and stopping the retraction of said platen while said pump is delivering said fluid toward said pull-back ram, electrical means for controlling the direction of delivery of said pump and of the forcible operation of said differential valve elements to control the direction of travel of said platen, said electrical means being operable by said platen during a retraction movement thereof for automatically reversing the delivery of said pump and forcibly operating said differential valve to automatically initiate a pressing operation of said platen after a desired return movement of the platen, said electrical means including a switch operated by said platen at one point in its return travel, and means for selectively nullifying the action of said switch when automatic reversal at the end of a retraction movement is undesired.

27. In a hydraulic press system, a platen, means for operating said platen in alternate directions, means including a stick relay and its circuit for controlling said operating means and having a closed circuit condition for said relay when operation of said platen in one direction is desired, switch means connected in the circuit of said relay for energizing said relay to initiate a movement of the platen in one direction, a timing device for opening said stick circuit and causing a reversal of the direction of travel of said platen, means operated by said platen during its travel in a pressing direction for rendering said timing device active, whereby said stick circuit will be opened a predetermined interval of time after the timing device is rendered active, and means for incapacitating said platen operated device and placing the timing device directly under the control of said relay to render the timing device active when said relay is closed, whereby the retraction of the platen may be started a predetermined interval of time either after the start of a pressing movement or after the platen passes a predetermined position in a pressing direction.

THOMAS F. STACY.
